US0D1086869S

(12) **United States Design Patent** (10) **Patent No.:** **US D1,086,869 S**
(45) **Date of Patent:** **** Aug. 5, 2025**

(54) **PACKAGING BOX**

(71) Applicant: **Samsung Display Co., Ltd.**, Yongin-si (KR)

(72) Inventor: **Yun Joo Yim**, Yongin-si (KR)

(73) Assignee: **Samsung Display Co., Ltd.**, Yongin-si (KR)

(**) Term: **15 Years**

(21) Appl. No.: **29/913,511**

(22) Filed: **Oct. 3, 2023**

(30) **Foreign Application Priority Data**

(57) **CLAIM**

The ornamental design for packaging box, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front view of a first embodiment of a packaging box in an unfolded state according to the present design; FIG. 2 is a front perspective view of the first embodiment of the packaging box in a folded state according to the present design;

FIG. 3 is a front view of a second embodiment of the packaging box in an unfolded state according to the present design; and,

FIG. 4 is a front perspective view of the second embodiment of the packaging box in a folded state according to the present design.

FlexMirror is a registered trademark from Samsung Display Co., Ltd. forming part of the claimed design.
